[57] CLAIM

The ornamental design for a table, as shown and described.

DESCRIPTION

FIG. 1 is an end elevational view of a table showing my new design, the opposite end being identical thereto;

FIG. 2 is a perspective view thereof;

FIG. 3 is a side elevational view thereof, the opposite side being identical thereto;

FIG. 4 is a top view thereof;

FIG. 5 is an end elevational view of a table showing a second embodiment of my new design, the opposite end being identical thereto;

FIG. 6 is a perspective view thereof;

FIG. 7 is a side elevational view thereof, the opposite side being identical thereto; and,

FIG. 8 is a top plan view thereof.

FIGS. 2, 4, 6 and 8 have been drawn on a reduced scale with respect to FIG. 1.
